Primary Examiner — Patricia A Palasik*(74) Attorney, Agent, or Firm* — Novick, Kim & Lee, PLLC; Jae Youn Kim; Hyun Woo Shin(57) **CLAIM**

We claim, the ornamental design for a cable transfer apparatus, as shown and described.

DESCRIPTION

FIG. 1 is a perspective view of a cable transfer apparatus, showing our new design;

FIG. 2 is a front elevational view thereof, a rear view being identical;

FIG. 3 is a left side elevational view thereof, a right side elevational view being identical;

FIG. 4 is a top plan view thereof; and,

FIG. 5 is a bottom plan view thereof.

1 Claim, 5 Drawing Sheets(56)
